UNITED STATES PATENT OFFICE.

WILLIAM CHRISTOPHER McLOUGHLIN, OF FITZROY, VICTORIA, AUSTRALIA.

SPINNING-MACHINE.

1,338,577.

Specification of Letters Patent. Patented Apr. 27, 1920.

Application filed November 7, 1919. Serial No. 336,528.

To all whom it may concern:

Be it known that I, WILLIAM CHRISTOPHER McLOUGHLIN, a subject of the King of Great Britain, residing at No. 369 Smith street, Fitzroy, in the State of Victoria, Commonwealth of Australia, have invented certain new and useful Improvements in Spinning-Machines, of which the following is a specification.

This invention has been devised to provide a machine whereby the spinning of fabrics will be more effectively and expeditiously accomplished than at present. In describing my invention, I shall refer to the spinning of what is known by those skilled in the art, as condensed woolen yarn, the individual fibers of which have been broken up in the condenser into the required slivers, the latter being drawn out or drafted during such step in the manufacture. The fibers are straightened, equalized, and combined, being finally wound on a bobbin in an attenuated, but strong uniform condition, providing a yarn suitable for the desired purpose.

In order that my invention may be the more easily understood, reference will be made to the accompanying drawings, in which—

Fig. 1 is a general view of a machine with apparatus embodying my invention. For sake of clearness, many of the duplicate parts of the machine have, for operation at the rear, been omitted. Some of the parts at the front of the machine have also been omitted for the same purpose.

Fig. 2 is an enlarged view of the bobbin, shroud and parts of same.

Fig. 3 shows drawn to a large scale, the retarder or flier hereinafter referred to.

Fig. 4 is an alternative construction of the retarder or flier.

Fig. 5 illustrates the arrangement of an endless belt for actuating the bobbins.

Fig. 6 illustrates apparatus for imparting a false twist to the sliver for strengthening purposes.

Fig. 7 illustrates an endless belt for actuating the apparatus shown in Fig. 6.

Fig. 8 is an enlarged view of a tubular arm hereinafter referred to.

Fig. 9 is a side elevation of the feed roller and carrier hereinafter described.

Fig. 10 illustrates a guide arm roller under which the sliver passes, while

Figs. 11 and 12 are respectively sectional

plan and front elevation of part of a raising and lowering mechanism hereinafter referred to.

In the accompanying drawings a frame is provided comprising preferably four standards *a* braced together by front, rear and side bars *a'* *b* and *b'* arranged in any convenient manner within the frame. On the top of the latter is the usual differential gearing *b*² receiving motion by an endless belt *b*³ running on pulley wheels *b*⁶, the operating power being transmitted from a main shaft *b*³, the gearing actuating the longitudinal feed rollers and carriers (hereinafter described) running at pre-determined speeds as hereinafter referred to.

The sliver *c* is fed from the spool *c'*, the spindle *c*² of which rests loosely on the diagonal arms *c*³ fixed in any convenient manner to the sides of the frame. From the feed roller *c*⁴ the sliver *c* passes downwardly, and in doing so, goes through the fingers *d* of the wire guard *d'* secured to a block *d*² on one of the frame bars *a'*. The sliver passes from the fingers *d'* between the roller *e* and carrier *e'*, the latter being mounted in bearings *e*² and driven by the gearing *b*² hereinbefore mentioned. The sliver *c* in its forward movement receives a twist to increase its strength for winding purposes, and the construction hereinafter described holds it should it break between the feed roller *e'* and the bobbin thus preventing it becoming entangled between the feed roller *e* and carriers *e'* and the gear, before the operating power is shut off.

The construction comprises two arms *f* mounted on the bar *a'* of the frame, one at each side, said arms *f* connected by a cross strap *f*¹ at the rear of which is disposed a parallel strap *f*², both straps held together by bolts *f*³ and form bearings for a rotary tube *f*⁴ with pulley *f*⁵. The projecting end of the tube *f*⁴ is cut away at about its center, the upper portion *f*⁶ (see Fig. 8) being fixed to an arm *f*¹⁰ hinged to a block *f*⁷ integral with the tube *f*⁴. The hinge *f*⁸ of *f*⁶ is so arranged that the weight of *f*⁶ will keep it continuously in contact, or nearly so, with the under half *f*⁹ of the tube *f*⁴. The pressure is such that it will not prevent the forward movement of the sliver *c* between the parts *f*⁶ and *f*⁹. The rotary action of the tube *f*⁴ has the effect of twisting the sliver *c* sufficiently to increase its tensile strength, thereby greatly reducing the pos-

sibility of a break while traveling between the carrier h and the bobbin.

The rotary tubes f^4 receive their motion through an endless belt g (see Fig. 7) arranged to pass over the pulleys f^5 and the tension pulleys g' and the drum b^4 on the main shaft b^3 . The tension pulleys g' are mounted on a spindle g^2 carried by an adjustable arm g^3 supported in a shaft g^4 running in bearings (not shown) in the side bars b' . The tension or load is adjusted by the weights g^6 at the end of the arm g^3 .

From the mouth of the tube f^4 the sliver c passes between a carrier h (see Fig. 1) and a tension roller h' mounted on an arm h^2 hinged to the rear parallel stay bar f^2 . The sliver c passes from the tension roller to a high speed rotary retarder or flier j preferably constructed of wire and bent to the required configuration, preferably with a U-shaped top portion j' or ring j^{10} forming director fingers and horizontal pieces j^2 one of which has a ring j^3 at its end.

The retarder or flier j rotates in a bearing at the top of a stationary shroud hereinafter described, the bearing consisting of a screw bolt j^4 with a central vertical slot j^5 (see Fig. 3) in which rotates the vertical supporting piece j^6 having at its bottom an enlarged cone shaped formation j^7 , acting as a stopper, and running in a circular shaped recess j^8 provided at the top of the stationary shroud k' (see Fig. 3).

The sliver c passes from the carrier h to, and under the U-shaped or ring portion j' and j^{10} the former forming fingers for leading purposes, and the latter for the same purpose also. The sliver c is led from j' or j^{10} to, and passed through the ring j^3 , which directs it on the curved edge k^3 of the bell mouth k^2 of the shroud k' .

To obviate undue vibration, and also to reduce the tension of the sliver c during the winding process, the retarder or flier is weighted at the end j^9 providing a counter balance effect against the strain placed on the other or ringed end j^3 .

Fixed vertically on the head of the spindle k is a shroud or bell k' of a hollow circular formation, the lower end k^2 being bell mouthed, its circular rounded edge k^3 acting as a director or guide to the sliver c to insure an even and parallel winding of the sliver c on to the bobbin. The latter is in the form of a tube m with a pulley m' at its bottom end, and is loosely mounted on the stationary spindle k . A stationary circular block m^2 which is supported by the bar o forms a boss upon which it rotates. The spindle k is fixed to a horizontal bar o^5 secured to the front of the frame, and forming part of the movable carriage hereinafter described. The bobbin receives its motion through an endless belt n arranged to pass around each of the pulleys m' and tension

pulley m^3 and the drum b^4 mounted on the main cross shaft b^3 (see Fig. 5).

The tension of the load is regulated by a weight m^4 on the bell crank m^5 mounted on the shaft g^4 . The shaft runs in bearings 70 fixed on the side bars o' of the frame. Any suitable power may be employed to actuate the main shaft b^3 and the drum b^4 .

The carriage comprises upper and lower cross bars o and o' , the former having a shelf o^2 attached for required purposes. The bars o and o' are connected to movable side guide rods o^3 operating vertically in guide blocks o^4 integral with the standards of the frame. The movement of the carriage is regulated so that as the sliver is wound around the bobbin, the latter becomes wider in diameter, and the winding point of the sliver, on the bobbin is raised or lowered accordingly. This action is accomplished 85 by providing for a vertical movement of the carriage, and also controlling the extent of such movement.

The carriages receive their vertical movement through the differential gear and carrier, the latter forming a shaft at the end of which a worm gear p is provided, actuating a toothed wheel p' on a side shaft p^2 running in bearings p^3 in one of the standards of the frame and side bars b' .

Mounted on one end of the shaft p^2 is a cam r which in its rotary movement actuates a rod r' , the top end of which operates in a bracket p^4 integral with the bar b' . The rod r' imparts motion to a lever rod 100 hereinafter referred to. The rod r' is provided with a handle r^2 to reverse the rotary motion of the rod r' when it is desired to lower the carriages to remove a bobbin and insert a fresh one on the spindle k .

The lower end of the rod r' is screw threaded and engages a block r^3 attached to a lever rod r^4 hinged to one of the standards a of the frame. The lever rod r^4 , in turn, operates the cord or cable r^5 passing over 110 the pulley wheel r^6 on the shaft r^7 running in suitable bearings (not shown), on the lower bar of the side bars b' .

Mounted on the cross shaft r^7 are pulley wheels r^8 and r^9 from which cords or cables 115 r^{10} pass, their lower ends being fastened to the bottom bar o' of the carriage.

Simultaneously with the vertical movement of the front carriage, a vertical movement is imparted to the rear carriage, a cord or cable s being employed one end being conveniently secured to the wheel r^8 and passed over a pulley s' , its end being fastened to the lower bar o' of the rear carriage.

The extent of the vertical movement of the carriage, when winding the sliver upon the bobbin, is regulated by a disk s^2 fixed at the end of the shaft p^2 . The disk has a number of adjustable strikers s^3 adjusted 130

according to the required speed of the shroud and bobbin. This regulation of speed is accomplished by causing the strikers s^3 to come into contact at a pre-determined time with a ratchet lever t , the return movement of which is controlled by the spring t' . One end of the ratchet lever t is provided with a spring locking pawl t^2 which engages the teeth of a ratchet wheel t^3 within the bracket p^4 , the wheel t^3 is keyed to the rod r' by a key t^4 passing through the boss t^5 of the wheel t^3 into a vertical key-way t^6 in the rod r' . This arrangement permits a vertical movement of the rod r' simultaneously holding the ratchet wheel t^3 .

10 A second spring controlled locking pawl u in the block u' is employed to retain the ratchet wheel t^3 at the end of each of its semi-rotating movements. The bent wires u^2 are employed as a handle when it is required to operate the pawls t^2 and u by hand.

15 I would have it understood that some of the parts may be amplified or modified to suit the various sizes of machines or the class of work to be performed, and the material to be treated.

I claim:—

1. In a spinning machine, the combination with stationary spindles, tubular bobbins mounted on the spindles, hollow shrouds carried with the spindles each being provided with a bell mouth and having a bearing at the upper end thereof, a rotary flier 30 mounted in the bearing and the rotary movement of said flier straightening, equalizing, and combining the fibers of wool or like material into an attenuated and strong uniform condition for winding on the bobbin.
2. In a spinning machine, a frame, a main driving shaft mounted thereon, differential gearing to which movement is imparted by the shaft, feed rollers and carriers actuated by the differential gearing, a vertically traveling carriage, stationary spindles, tubular bobbins rotatably mounted on the spindles, hollow shrouds carried with the spindles each being provided with a bell mouth and having a bearing at the upper end thereof, a rotary flier mounted in the bearing and the rotary movement of said flier straightening, equalizing, and combining the fibers of wool or like material into an attenuated and strong uniform condition for winding on the bobbin.

55 bin.

3. In a spinning machine, a frame having standards, a main rotatable driving shaft in the frame, differential gearing operably connected with the shaft, feed rollers and carriers operated by the gearing, a carriage, means for imparting a vertical movement to the carriage, a carrier shaft, a worm gear on the carrier shaft, another shaft engaged by the worm gear, a cam on the last mentioned shaft, a vertical rod 60 in contact with the cam and actuated thereby, a lever bar connected to said rod, a cable connected to the lever bar, a cross shaft, a main pulley wheel mounted on the cross shaft and over which the cable 65 runs for actuating said pulley wheel, two side pulley wheels on the cross shaft, the rotary movement of the last mentioned pulley wheels raising or lowering the carriage, said carriage comprising horizontal bars and 70 guide rods on the horizontal bars, guide blocks on the standards of the frame in which the guide rods operate, circular bosses supported by one of said bars and upon which bobbins are adapted to rotate, pulley 75 wheels with bearings at each side of the standards and cables running on the last mentioned pulley wheels and having their ends fastened to the lower bar of the rear carriage, substantially as and for the purposes set forth.

4. In a spinning machine, a frame, gearing actuated carriages mounted on the frame, a rotary shaft, a disk on one end of the shaft, strikers on the disk, a ratchet lever 90 operated by the contact of the strikers therewith during the rotary movement of the shaft, a return controlling spring for the lever, a spring locking pawl for the lever, a vertically actuating screw rod having a 95 handle, a ratchet wheel keyed to the rod and engaged by the spring pawl, a locking pawl for retaining the ratchet wheel when required, pulley wheels associated with the carriage, a lever rod and cables connected 100 with the lever rod for operating the pulley wheels so as to consequently raise or lower the carriages, substantially as described and for the purposes set forth.

In testimony whereof I affix my signature 105 in the presence of two witnesses.

WILLIAM CHRISTOPHER McLOUGHLIN.
